UNITED STATES PATENT OFFICE

2,455,601

PRODUCTION OF SOLVENTS

Lloyd C. Morris, Bartlesville, Okla., assignor to
 Phillips Petroleum Company, a corporation of
 Delaware

Application June 6, 1946, Serial No. 674,701

6 Claims. (Cl. 260—671)

1

This invention relates to solvents having very low odor intensity and to methods for the production of such solvents. In one particular aspect it relates to a continuous combination process for the production of solvents from selected hydrocarbons wherein low odor intensity results from a non-oxidative steam fractionation and solvent power is provided and controlled in alkylation and blending steps. In another particular aspect it relates to novel solvents obtained by blending cyclic and paraffinic hydrocarbons.

The dry cleaning, insecticide, printer's ink and paint industries have long desired odorless solvents. For many years straight run naphthas deodorized by treatment with strong sulfuric acid and caustic have been the most nearly odorless materials obtainable. These deodorized naphthas still have much odor and frequently lack desired solvent power.

Completely odorless solvents have recently been prepared by methods taught in the copending applications of Legatski and Crawford, Serial No. 616,930 filed September 17, 1945, and Crawford and Morris, Serial No. 617,870 filed September 21, 1945. However the above-mentioned industries for some uses frequently require solvents which have not only low odor intensity but also high solvent power, suitable color, definite flash point and the like. Solvents having the required characteristics are often very difficult to prepare at reasonable cost. For example, cyclic hydrocarbons such as benzene and its derivatives, naphthenes and the like have high solvent power, usually coupled with undesirable odor, and are expensive, while the paraffin materials which are cheaper and less odorous generally have lower solvent power. Furthermore maintenance of desirable odor characteristics in paraffins often presents difficulties. For example the highly branched paraffins such as diisopropyl or heavy alkylate fractions from mixtures produced by catalytically activated interaction of low-boiling isoparaffins and short chain olefins appear to be among the best from the standpoint of odor but when stored for long periods, heated or fractionated in the presence of air these products develop objectionable odors.

It is an object of this invention to provide solvents having low odor intensity and controlled solvent power.

Another object is to provide a process for preparing solvents having low odor intensity from paraffinic, aromatic and olefinic feed stocks.

Another object is to provide a process for pre-

2

paring solvents having low odor intensity and controlled solvent power.

Another object is to provide a method for the production of solvents from hydrocarbon feed stocks wherein low odor intensity is secured by a non-oxidative steam fractionation step and solvent power is controlled by alkylation and blending steps.

Other objects and advantages will become apparent to those skilled in the art as this disclosure proceeds.

I have now found that substantially odorless solvents having controlled solvent power may be produced by a process comprising the steps: 15 (a) distilling low odor paraffinic hydrocarbons with steam under non-oxidizing conditions to produce cuts of desired boiling range, (b) catalytically alkylating an aromatic hydrocarbon with a high-boiling olefin, and (c) blending aromatic 20 alkylate from step (b) with a low odor paraffinic fraction from step (a).

The accompanying drawing illustrates diagrammatically one preferred embodiment of the process of my invention. In order to simplify 25 the explanation and also to provide an example of the process and solvents of my invention the particular embodiment thereof wherein feed stocks comprising heavy alkylate from a hydrofluoric acid alkylation process, benzene, 30 and a high-boiling olefinic material are used is shown and described. Limitation of the invention to the materials and conditions of this embodiment is neither implied nor intended.

Referring to the diagram, a low odor paraffinic 35 feed stock, in this instance heavy HF alkylate boiling above 300° F., is introduced into the distilling column 1 via line 2 containing pump 3 from storage 4. Distillation is effected by a stream of air-free steam introduced through line 5. Vapors 40 from this column are discharged through line 6 containing cooler 7 into the water separator 8, where the condensate separates into water and hydrocarbon phases. The water phase is removed through line 9 containing valve 10. During the 45 distilling operation, a suitable inert gas such as a methane-hydrogen mixture, is injected into the system at points 11, 12, and 13, from line 14, thereby maintaining an oxygen free atmosphere for this process. It may be preferred to blow the 50 gas through the feed stock as shown, thereby driving out dissolved air which may be present. Provision for venting this gas is made by lines 15 and 16.

Concurrently with the foregoing operation, a 55 suitable aromatic substance, in this instance ben-

zene, from storage 17 is commingled with a high-boiling olefinic concentrate from storage 18 and introduced into the alkylation chamber 19 through line 20 containing pump 21. A suitable alkylating catalyst such as a boron fluoride complex composition introduced through line 22 containing pump 23 from storage 24 is admixed with the aromatic-olefin mixture while conditions in the reactor are maintained at an optimum level for substantially complete conversion of the olefins 10 to alkyl benzenes.

When operating with the high density boron fluoride complex catalysts, recycling of the heavy catalyst material is effected through lines 25 and 22 by pump 23. Effluent from the alkylation chamber is discharged through line 26 to the catalyst separator 27 where gravity separation into hydrocarbon and catalyst phases occurs. The heavy catalyst phase is restored to the circulating catalyst stream through line 28, while the hydrocarbon phase flows through line 29 to the washer 30 where traces of catalyst are removed. The effluent stream then passes through line 31 to the drier 32 and from thence to the stripping column 33 via line 34 containing pump 35. Unreacted benzene is driven overhead through the recycle line 36 to storage 11. Crude alkylate is conveyed to the vacuum fractionator 37 via line 38 containing pump 40. Light ends and heavy bottoms are removed through lines 41 and 42 respectively, and purified alkyl benzenes are discharged through line 43 containing valve 44. The low odor paraffin mixture from separator 8 is drawn through line 45 containing valve 46 and commingled with the alkyl benzene from line 43 in line 47 containing pump 48. By suitable adjustment of valves 44 and 46, solvent power of the product may be adjusted as desired.

In the practice of the invention, the paraffinic feed stock employed should be a low odor material since more efficient operation can be secured with such stocks. However, slightly off-odor materials can often be employed; if the first fraction obtained is discarded or otherwise utilized, since the malodorous products usually are removed in this manner.

In the alkylation step, the aromatic substance may be benzene or its homologues, xylenes, or other like substances. The olefinic alkylating agent may comprise high-boiling olefins or olefin mixtures boiling in the range between 200 and 500° F. and including olefins of not less than seven or more than 18 carbon atoms to the molecule. A preferred source of such mixtures is found in the 200 to 500° F. fraction from catalytically cracked gas oils or high boiling naphthas, such as, for example, those produced in a Cycloversion process.

By suitable adjustment of the boiling range, low odor solvents of high solvent power can be manufactured for use in various specific processes. Obviously this range will be limited by the particular fractions employed as feed stocks. When operating with the highly branched alkylates hereinbefore mentioned, solvent fractions boiling between about 325 and about 550° F. can be produced. In instances where very high solvent power is desired, the larger proportion of aromatic alkylate may provide even higher boiling fractions should such be desirable.

Example I

Employing the process of the present invention, a solvent was prepared from feed stocks comprising heavy HF-alkylate, benzene, and a Cycloversion olefin concentrate boiling in the range 350

to 400° F. The operation was conducted in a manner to produce a low odor solvent boiling in the range 350 to 450° F. and with moderate solvent power. Properties of the product were as follows:

API gravity (60° F.)	51.3
Index of refraction (20° C.)	1.434
Bromine number	Zero
Aniline point	71.4
Kauri-butanol value, cc.	35.0
Flash point, °F.	130.0
Odor	Good

Example II

The process of Example I was repeated employing the same feed stocks but in a manner to produce a low odor solvent boiling in the range 350 to 450° F. and with high solvent power. Properties of the product were as follows:

API gravity (60° F.)	38.6
Index of refraction (20° C.)	1.475
Bromine number	Zero
Kauri-butanol value, cc.	80
Flash point, °F.	130
Odor	Good
Aniline point, °F.	25

A significant feature of the present process lies in the manner of fractionation employed to provide cuts boiling in the desired range. Distillation is effected by the use of steam, thus reducing the fractionation temperature. By operating in this manner the tendency toward odor development often observed when the feed stock is heated at or near the boiling point is substantially reduced. By the employment of air-free steam in the distillation and the exclusion of air from the system by suitable flushing with inert gas any deterioration of the product by oxidative processes is substantially eliminated and the preferred low odor characteristics of the feed stock are maintained.

Another advantage of the invention lies in the alkylation step whereby solvent power in the product is regulated over a broad range. The aromatic alkylate produced in this step is of very high solvent power and when commingled with the low odor paraffinic fractions produced in the distillation step, contributes solvent power in a direct ratio with the proportion present. By suitable adjustment of this step solvents can be prepared for a variety of uses. For example, where it is desired to prepare a solvent for insecticides in which the concentration of active base is say 5 per cent, the alkylation step is operated at a low rate, since a very small proportion of cyclic constituents will provide ample solvent power. If, on the other hand, a concentration of 50 per cent active base were desired, a suitable solvent could be prepared by adjusting the alkylation step to provide a larger proportion of the product stream, whereby the increased solvent power would be obtained.

Having described my invention and explained its operation, I claim:

1. A process for producing a solvent having low odor intensity and controlled solvent power which comprises: fractionating the product resulting from hydrofluoric acid alkylation of a low-boiling isoparaffin with a short chain olefin; withdrawing a fraction boiling above 300° F.; removing dissolved oxygen from said fraction by blowing an inert odorless gas therethrough; steam distilling said fraction with air-free steam; maintaining

non-oxidizing conditions in such distillation by injecting inert odorless gas; withdrawing an overhead product comprising water and hydrocarbons; introducing said overhead product and inert, odorless gas into a settling zone and separating the liquids therein into a substantially odorless hydrocarbon layer and a water layer; withdrawing said hydrocarbon layer: concomitantly alkylating benzene with a high-boiling olefin concentrate from a process for catalytically cracking high-boiling naphtha in the presence of a catalyst comprising boron fluoride; separating residual benzene and catalyst from the resulting aromatic alkylate; distilling said aromatic alkylate under vacuum in a fractionation zone; withdrawing a fraction of aromatic alkylate; blending said fraction of aromatic alkylate with said substantially odorless hydrocarbon layer withdrawn from said settling zone; and controlling the solvent power of the resulting solvent by controlling the percentage of aromatic alkylate added thereto.

2. A process for producing a solvent having low odor intensity and controlled solvent power which comprises: fractionating the product resulting from alkylation of a low-boiling isoparaffin with a short chain olefin; withdrawing a fraction boiling above 300° F.; removing dissolved oxygen from said fraction by blowing an inert odorless gas therethrough; steam distilling said fraction with air-free steam; maintaining non-oxidizing conditions in such distillation by injecting inert odorless gas; withdrawing an overhead product comprising water and hydrocarbons; introducing said overhead product and inert, odorless gas into a settling zone and separating the liquids therein into a substantially odorless hydrocarbon layer and a water layer; withdrawing said hydrocarbon layer: concomitantly alkylating an aromatic hydrocarbon with a high-boiling olefin; separating residual aromatic hydrocarbon and catalyst from the resulting aromatic alkylate; distilling said aromatic alkylate under vacuum in a fractionation zone; withdrawing a fraction of aromatic alkylate; blending said fraction of aromatic alkylate with said substantially odorless hydrocarbon layer withdrawn from said settling zone and controlling the solvent power of the resulting solvent by controlling the percentage of aromatic alkylate added thereto.

3. A process for producing a solvent having low odor intensity and controlled solvent power which comprises: distilling a mixture of highly branched paraffin hydrocarbons with air-free steam; maintaining non-oxidizing conditions in such distillation by injecting inert, substantially odorless gas; withdrawing a substantially odorless fraction; blending said fraction with a fraction of aromatic alkylate produced by vacuum distilling the product formed by catalytically alkylating an aromatic hydrocarbon with a high-boiling olefin; and controlling the solvent power of the resulting solvent by controlling the proportion of aromatic alkylate therein.

4. A process for producing a solvent having low odor intensity and controlled solvent power which comprises: distilling an alkylation product comprising a mixture of highly branched paraffin hydrocarbons with air-free steam; maintaining non-oxidizing conditions in such distillation by injecting inert, substantially odorless gas; withdrawing a substantially odorless fraction; blending said fraction with a fraction of aromatic alkylate produced by vacuum distilling the product formed by catalytically alkylating an aromatic hydrocarbon with an olefin having from 7 to 18 carbon atoms; and controlling the solvent power of the resulting solvent by controlling the proportion of aromatic alkylate therein.
5. A process for producing a solvent having low odor intensity and controlled solvent power which comprises: distilling an alkylation product comprising a mixture of highly branched paraffin hydrocarbons with air-free steam; maintaining non-oxidizing conditions in such distillation by injecting inert, substantially odorless gas; withdrawing a substantially odorless fraction; blending said fraction with a fraction of aromatic alkylate produced by vacuum distilling the product formed by catalytically alkylating an aromatic hydrocarbon with an olefin mixture boiling in range from 200 to 500° F.; and controlling the solvent power of the resulting solvent by controlling the proportion of aromatic alkylate therein.
6. A solvent having high solvent power and low odor, consisting of a highly branched paraffinic HF alkylate boiling above 300° F. in admixture with an alkylated benzene wherein the alkyl group contains at least 7 and not more than 18 carbon atoms, said solvent having the following properties:

Boiling range, ° F.	350-450
API gravity (60° F.)	38.6
Index of refraction (20° C.)	1.475
Bromine number	Zero
Kauri-butanol value, cc.	80
Flash point, ° F.	130
Odor	Good
Aniline point, ° F.	25
